UNITED STATES PATENT OFFICE.

HENRY RICHARDSON, OF CHICAGO, ILLINOIS.

CORNER LOCK FOR BEDSTEADS.

Continuation of application Serial No. 519,871, filed December 5, 1921. This application filed January 16, 1922. Serial No. 529,445.

To all whom it may concern:

Be it known that I, HENRY RICHARDSON, a subject of the King of Great Britain, residing at Chicago, in the county of Cook and State of Illinois, have invented certain new and useful Improvements in Corner Locks for Bedsteads, of which the following is a specification.

This invention pertains to improvements 10 in what are commonly known as corner locks for bedsteads, including the instrumentalities by which the side rails or end rails of a bedstead frame, or the side rails of a bed spring are separably united to the corner posts of 15 the bedstead frame.

An important object of the invention is to provide a simple means for strongly and rigidly locking the side or end rails or both to the corner post bracket preferably formed 20 of sheet metal that shall be self-locking and will securely hold the side rail in the bracket and will maintain the perfect rectangular relation in a vertical plane of the corner post and side rail, preventing any tipping or canting 25 of the former either under the weight carried by the bed frame or under longitudinal pulling strains. A still further object of the invention is to provide an improved construction of corner bracket and locking means 30 that, in addition to the advantages above pointed out, will permit the side rails to be inverted so as to support either a bed spring frame or slats.

Other objects and attendant advantages of 35 the invention will be apparent to persons skilled in the art as the same becomes better understood by reference to the following detailed description, taken in connection with the accompanying drawings, wherein I have 40 shown several specific forms or embodiments of the principle of the invention, and in which—

Fig. 1 is a side elevation of my improved bracket shown applied to a corner post, and 45 with the side and end rails secured thereto by my improved locking means;

Fig. 2 is a front elevation of the same, in section through the side rail;

Fig. 3 is a perspective elevation of the side rail attachment that enters and interlocks 50 with the corner bracket;

Fig. 4 is a top plan view of Fig. 2, in horizontal section through the bed post;

Fig. 5 is a horizontal section through the corner bracket on the line 5—5 of Fig. 55 6;

Fig. 6 is an enlarged vertical section through the corner bracket on the line 6—6 of Fig. 5;

Fig. 7 is a plan view of a sheet metal blank 60 from which the side rail attachment is formed;

Fig. 8 is a view similar to Fig. 2, showing the side rail applied in inverted position;

Figs. 9, 10, 11 and 12 are views corresponding to Figs. 1, 2, 3 and 4, respectively, showing a square corner post and a modification of the locking devices in the side walls of the bracket and side rail attachment;

Fig. 13 is a plan view, similar to Fig. 7, 70 of a sheet metal blank from which the side rail attachment shown in Fig. 11 is formed;

Fig. 14 is a vertical cross section through the side rail attachment illustrating a modification of the side locking element. 75

The present invention is of that type which preferably employs a box-like sheet metal bracket on the corner post and a side rail of either the bedstead frame or a spring frame having an end, or end attachment 80 thereof, entered in the said bracket; and the novel features relate mainly to improved means for removably self-locking the side rail, or rail attachment, to the bracket, said locking means being designed to accomplish 85 as its principal object the maintenance of a rigid rectangular relation in a vertical plane of the side rail and the corner post of the bed frame, and prevent any tipping or canting 90 of the corner post either under a load on the bed frame or by pulling or pushing the latter over the floor, it being well known that the latter operation involves a severe bending strain on the corner brackets and the side rail fastening means. 95

Referring first to the form of the invention illustrated in Figs. 1 to 8 inclusive, 1 designates a round corner post of a bed frame, to which is secured a box-like bracket 100 comprising a rear wall 2, parallel outer and inner side walls 3 and 4, and a bottom wall or plate 5. Where this bracket is made from sheet metal it is cut and bent to the shape shown. The side walls 3 and 4 may consist of integral forward extensions from the back plate 2, and the bottom wall or plate 5 may 105

consist of an upwardly bent extension of the side wall 3. To provide support for the free edge of the bottom plate 5, the inner side wall 4 may be provided on its lower edge 5 with an integral extension or flange 6 bent upwardly beneath the free edge of the bottom plate 5, as clearly shown in Figs. 2, 5 and 6. For the attachment of an end rail 7, the bottom plate 5 is formed with a horizontal extension 8, and the lower portion of the back plate 2 is formed with a lateral vertical extension 9 to which extension lugs the horizontal and vertical limbs of the end rail 7 are secured by rivets 10 and 11. The back plate 2 is attached to the corner post by suitable bolts 12.

13 designates a side rail, which may be either a side rail of the bed frame or a side rail of a spring frame. To each end of this 20 side rail is secured a specially formed extension that enters and co-operates with the corner bracket. Where this extension member is made of sheet metal, as is preferable, it is cut and bent to shape from a flat blank 25 shown in Fig. 7, wherein 14 and 15 form the top and bottom horizontal walls, 16 the outer side wall, and 17 and 18 together constitute the inner side wall. The parts are bent at right angles on the dotted lines shown in 30 Fig. 7, and, for the purpose of increased rigidity, the complementary side wall sections 17 and 18 are formed, one with a notch 19 and the other with a tongue 20 fitting said notch. The top wall 14 and outer side 35 wall 16 are formed with integral longitudinal extensions 21 and 22 constituting the attachment lugs by which the extension member is secured to the side rail through rivets 23.

40 In the bottom plate 5 of the bracket is rigidly secured an upstanding stud 24, and the top and bottom plates 14 and 15 of the rail extension member are formed with holes 25 and 26, respectively, the hole 26 being engaged with the stud 24 when the side rail is in upright position, as shown in Figs. 1, 2 and 3, and the hole 25 being engaged with the stud 24 when the side rail is applied in inverted position, as shown in Fig. 8.

50 In this form of the invention the stud 24, in co-operation with the holes 25 and 26, constitutes the lower locking means. I will next describe one form of upper locking means which may be used in co-operation 55 with the lower locking means to insure the locking of the side rail to the bracket and the angular rigidity of the side rail and corner post.

Secured in and extending between the side 60 walls 3 and 4 of the bracket is a pin 27 which bonds said walls together. In the outer side wall of the extension member are opposed upper and lower vertical notches 28 and 29, and in the inner side wall of the extension member are corresponding upper and lower

vertical notches 28' and 29'. The notches on each side are provided with a common entrance slot 30, 30' that extends lengthwise of the outer portion of the side wall, as best shown in Fig. 3. In entering the rail extension into the bracket, the slots 30, 30' pass over the pin 27, and as the latter comes into the vertical plane of the vertical notches, the rail is lowered, bringing the notches 28 and 28' into engagement with the pin 27 if the rail is upright, and the notches 29, 29' into engagement with the pin if the rail is inverted. As the rail extension is thus lowered into locking engagement with the pin 27, simultaneously the hole 26 or 25 engages with the stud 24. The pin 27 thus co-operates with the stud 24 in opposing pulling out strains and bending strains in a vertical plane between the side rail and post, and also partly relieves the bottom plate 5 of the bracket from the strain of the weight carried by the bed.

In the form of the invention illustrated in Figs. 9 to 13 inclusive, the corner bracket is identical with that already described, but the rail extension member and its upper locking means are slightly varied, and are of such a nature as to permit the rail to be self-locked to the bracket under a simple relative vertical movement of the parts. The sheet metal blank from which the extension member is formed, and which is shown in Fig. 13, includes side plates 30 and 31 and top and bottom plates 32 and 33, bent into box form on the dotted lines shown in Fig. 13, with integral attachment lugs 34 and 35 on the said walls 31 and 32 respectively for securing the attachment to the side rail 13. In this construction the side walls of the bracket are formed with vertical slots 36; and the side walls of the rail extension member are equipped with headed studs 37 that, as the rail is engaged with the bracket, slide downwardly through the slots 36 and come to rest in the lower ends of the latter simultaneously with the engagement of the stud 24 with one of the holes 25, 26 of the extension member. The studs 37 being located mid-height of the extension member obviously serve to support the side rail in either upright or inverted position. In Figs. 9, 10 and 11 I have shown the bracket applied to a square post 1^a, but obviously the cross sectional form of the post is immaterial, since the rear wall of the bracket is readily shaped to conform to and fit the same. To permit the end of the rail extension member to readily pass the head of the upper fastening bolt 12 I have shown the top and bottom walls 32 and 33 notched out 125 at 38.

In lieu of using separate studs 37 I may replace the same by a single transverse pin 39 mounted in and extending between the side walls 30 and 31 of the rail extension, 136

with a central enlargement or spacing sleeve 40, as shown in Fig. 14.

Another important advantage of the present invention is that it provides reversibly 5 acting interlocking means adapted to automatically fasten an end of a side rail within a bracket under a downward movement and to hold the side rail and bed post against relative horizontal movement and relative 10 angular movement in a vertical plane in either the upright or inverted position of the side rail. Since the side rail attachment members herein shown are rigidly and permanently fastened to the side rail proper 15 and constitute in effect end portions of the latter, it is to be understood that wherever the ends or end portions of the side rail are referred to in this specification or in the claims, I have meant to designate either 20 integral end portions, or attached end portions, of the side rails. The term "side rail" as used herein is intended to include either the side rail of a bed frame or the side rail of a bed spring frame.

25 It is believed that the foregoing description in connection with the drawings will make clear to those skilled in the art the novel structural features of the present invention and the principle underlying the same. Manifestly the forms shown and described by no means exhaust the structural variations and modifications that are possible 30 within the principle of the invention, but they are believed to be sufficient to make clear the structural and functional advantages which inhere therein. While I have herein shown the co-operating interlocking means as consisting of pins and slots, I do not limit such means to these specific devices 35 which manifestly may be substituted by any projecting members integral or otherwise on one part interfitting with slots or recesses in the other. Hence, I do not limit the invention to the specific forms, arrangements 40 and proportions shown in the drawings, but reserve all such variations and modifications as fall within the spirit and purview of the appended claims.

I claim—

50 1. In a corner lock for bedsteads, the combination of a bracket, an angular side rail entered within said bracket having its vertical wall engaged with a vertical wall of the latter by means of upper co-operating rail locking elements on the said walls interlocking with one another through a relative vertical movement of the said elements, whereby the said bracket and side rail are held against relative horizontal movement, and lower co-operating rail locking elements 55 on the end portion of the said side rail and a horizontal member of the said bracket interlocking the said end portion with the said horizontal member and acting jointly with the said upper co-operating rail locking ele-

ments to hold the said bracket and side rail against relative angular movement in a vertical plane.

2. In a corner lock for bedsteads, the combination of a bracket comprising a back 70 wall adapted to fit the bed post, a side wall, and a horizontally disposed member, a side rail having an end portion provided with upper and lower horizontal walls disposed within the said bracket, an upper rail locking element on the said side wall of the bracket and a vertical limb of the said side rail end portion co-operating, under a relative vertical movement, to interlock the said side wall with the said vertical limb, and a lower rail locking element on one of the said horizontal walls and the horizontally disposed member of the bracket co-operating to interlock the said horizontal member of the side rail with the said horizontally disposed member of the bracket. 85

3. In a corner lock for bedsteads, the combination of a bracket comprising a back wall adapted to fit the bed post, a side wall projecting outwardly from the said back wall, and a horizontally disposed member, a side rail end portion provided with upper and lower horizontal limbs disposed within the said bracket, an upper rail locking element on a vertical limb of the said side rail end portion co-operating with an upper rail locking element on the side wall of the bracket to interlock the said vertical limb with the said side wall in either the upright or inverted position of the said side rail, and lower means for locking a horizontal limb of the said side rail end portion to the said horizontally disposed member of the bracket in either the upright or inverted position of the said side rail, said means also co-operating with the said upper co-operating rail locking elements to hold the said bracket and side rail against relative angular movement in a vertical plane. 100 105

4. In a corner lock for bedsteads, the combination of a bracket, an angle iron side rail having its vertical wall interlocked with a vertical wall of the said bracket on the inner side of said bracket wall by upper locking means including a pin on one of the said walls interlocking with a slot in the other of the said walls under a relative vertical movement of the said slot and pin, and lower means for locking a horizontal member of said angle iron side rail to a horizontally disposed member of the said bracket. 110 115 120

5. In a corner lock for bedsteads, the combination of a bracket, a side rail having a vertical wall engaged with a vertical wall of the said bracket by means of a pin carried by one of said portions and interlocking with a slot in the other of said portions, and means for interlocking a horizontal member of the said side rail with a bottom plate of the said bracket, comprising an upstanding 125 130

pin on the said bottom plate engaged with an aperture in the horizontal member of said side rail.

6. In a corner lock for bedsteads, the combination of a bracket having a back plate adapted to be secured to a bed post, and outer and inner side plates, a pin mounted on and bonding together the upper portions of said side plates, a side rail having a vertical end portion entered within said bracket, said end portion being provided with a T-shaped slot adapted to engage with the said cross-pin under a downward movement of said side rail in either the upright or inverted position of the latter, and lower reversibly acting auxiliary means on the said bracket and side rail brought into operative engagement under the said downward movement of the side rail and locking the latter against endwise withdrawal from said bracket.

7. In a corner lock for bedsteads, the combination of a box bracket, a side rail having an end portion including outer and inner vertical limbs adapted to engage within and between the side walls of said bracket, co-operating pin-and-slot means on the said bracket and side rail end portion, brought into co-operative engagement by a relative vertical movement of said rail end portion and bracket, for locking said parts against separation in a horizontal direction in either the upright or inverted position of said side rail, and other co-operating pin-and-slot means on the said outer and inner vertical limbs of the side rail end portion and the side walls of the bracket also brought into co-operative engagement by a relative vertical movement of said rail end portion and bracket, and co-operating with said first named pin-and-slot means to hold said side rail and bracket against relative angular movement in a vertical plane in either the upright or inverted position of said side rail.

8. In a corner lock for bedsteads, the combination of a box bracket having vertically slotted side walls, a side rail having an end portion including outer and inner vertical limbs adapted to engage within and between the side walls of said bracket, co-operating pin-and-slot means on the said bracket and side rail end portion, brought into co-operative engagement by a relative vertical movement of said rail end portion and bracket, for locking said parts against separation in a horizontal direction in either the upright or inverted position of said side rail, and outwardly projecting pins on the side walls of said side rail end portion engaging with the vertical slots in the side walls of said bracket under a relative vertical movement of said rail end portion and bracket, and co-operating with said first named pin-and-slot means to hold said side rail and bracket against relative angular

movement in a vertical plane in either the upright or inverted position of said side rail.

9. A sheet-metal bracket for bedsteads, comprising integral rear, side and bottom walls, horizontal and vertical attachment lugs for an end rail, said horizontal lug constituting an extension of said bottom wall, and said vertical lug constituting an extension of said back wall extending below the plane of said bottom wall.

10. In a corner lock for bedsteads, the combination of a bracket comprising a back plate adapted to fit the bed post, and outer and inner side plates, and a horizontal bottom plate between the latter, a side rail end portion having outer and inner vertically disposed plates fitting between the said outer and inner side plates of the bracket, and a horizontal bottom plate, a rail locking element on each side wall of the bracket interlocking with a co-operating rail locking element on each vertical member of the said side rail end portion, and a pin on one of said bottom plates co-operating with an aperture in the other of said bottom plates.

11. In a corner lock for bedsteads, the combination with a box-like bracket having a cross-pin mounted in and between its side walls, of a side rail end portion having spaced vertical walls and formed with opposed vertical notches in said vertical walls and central longitudinal entrance slots communicating at their inner ends with said vertical notches, whereby said end portion may be entered into said bracket under an endwise movement and is supported and prevented from pulling out by the engagement of a pair of said notches with said cross-pin in both upright and inverted positions of said side rail, and interlocking means on said bracket and side rail end portion co-operating with said cross-pin and the vertical notches engaged thereby to hold said side rail and bracket against relative angular movement in a vertical plane.

12. In a corner lock for bedsteads, the combination of a sheet-metal bracket comprising a post plate for attachment to a corner post or bed, a straight vertical outer side plate, and an inner side plate, and bonding means consisting of a pin immediately facing said post plate for bonding said side plates together, said pin also constituting an upper rail locking element, an angle side rail entered within and lying wholly between the outer and inner side plates of said bracket having a vertical limb thereof formed with a vertical slot constituting an upper rail locking element adapted to lockingly engage with said pin, said side rail having its end portion beyond said slot extending between the said bonding means and post plate, and lower rail locking means on the said bracket and side rail end

portion comprising a member projecting from one of said parts interfitting with a recess in the other of said parts.

13. In a corner lock for bedsteads, the combination of a sheet-metal bracket having a post plate, outer and inner side walls and a bottom plate, an upper rail locking element comprising a cross-pin mounted on and bonding said outer and inner side walls to one another, a side rail having an end portion entered within said bracket, said end portion being provided with an upper vertical rail locking slot embracing said cross-pin, and lower rail locking elements on said end portion and the said bottom plate of the bracket, said last-named elements comprising a member projecting from one of said parts interfitting with a recess in the other of said parts under a relative downward movement of said side rail and bracket.

14. In a corner lock for bedsteads, the

combination of a sheet metal bracket having a back wall and outer and inner side walls, a pin bonding said side walls together and forming an upper rail locking element, a horizontal member inwardly bent from the lower edge of said outer side wall, an end rail attached to said horizontal member, and, through the latter, opposing outward bending of the lower portion of said outer side wall, a side rail engageable within said bracket and formed with a vertical slot embracing said pin, said side rail having its end portion beyond said slot extending between the said pin and the back wall of the bracket, and lower rail locking elements comprising co-operating means on said side rail end portion and the lower portion of said bracket respectively locking said side rail against endwise withdrawal from said bracket.

HENRY RICHARDSON.
